UNITED STATES PATENT OFFICE.

ELIEL L. SHARPNECK, OF CHICAGO, ILLINOIS, ASSIGNOR TO THE IDEAL REFRIGERATING AND MANUFACTURING COMPANY, OF COLORADO SPRINGS, COLORADO.

COMPRESSOR FOR ICE-MACHINES.

SPECIFICATION forming part of Letters Patent No. 636,459, dated November 7, 1899.

Application filed October 1, 1897; Serial No. 653,725. (No model.)

To all whom it may concern:

Be it known that I, ELIEL L. SHARPNECK, a citizen of the United States, residing at Chicago, in the county of Cook and State of Illinois, have invented a new and useful Improvement in Ice-Machines, of which the following is a specification.

My invention relates to an improvement in ice or refrigerating apparatus generally and of the class wherein a gas, such as anhydrous ammonia, liquefiable under mechanical compression is employed as the refrigerating agent.

While my invention is not to be confined to apparatus of any especially-limited capacity or for any specific use, my improvements for the most part are designed more particularly for use in connection with the smaller types of individual refrigerating plants—such, for example, as are adapted for employment in cooling butchers', grocers', or domestic store-rooms or for the manufacture of ice in the smaller towns or in private establishments. While it is naturally desirable in apparatus of this class to reduce the initial cost of construction as much as possible consistent with strength, durability, and effectiveness, the improvement which produces the greatest economy in the end is one that reduces the operating expenses by increasing the capacity for refrigeration with relation to the power employed. Individual refrigerating plants are coming largely into use in places where power for running the plants, either electrical or steam, is rented. The rental is governed by the horse-power required, and any reduction in the power necessary for operating a plant of a given capacity is one of daily economy, always to be desired and sometimes vitally necessary. Although the use of natural ice in establishments such as butcher-shops is attended with more or less trouble, discomfort, and uncleanliness, refrigerating plants intended to compete with and supersede the use of natural ice must not in the majority of cases be materially more expensive than natural ice in the end. Refrigerating plants of the class to which my invention relates employ, generally

stated, a close refrigerating-chamber in which are located refrigerating-coils, a compressor actuated by any suitable power and operated to suck and compress the return gas from the refrigerating-coil, a condenser to which the compressed gas is discharged by the compressing device, and a storage-receptacle which receives the condensed gas or liquid from the condenser and from which the liquid flows to expand in the refrigerating-coils.

My object is to provide a generally-improved refrigerating apparatus of the class above defined employing a compressing-machine which shall have comparatively great capacity for compressing and discharging the return gas, while requiring comparatively little power for its operation and avoiding the discharge of any appreciable amount of oil into the refrigerating-coils and employing other improvements in various parts of the apparatus, all tending toward economy in construction, space, and operation, as well as toward efficiency, durability, and simplicity.

In the drawings, Figure 1 is a longitudinal vertical section through the compressor with certain details, however, in elevation; Fig. 2, a transverse section taken on line 2 of Fig. 1 and viewed in the direction of the arrow; Fig. 3, an enlarged section of the upper part of the compressor, the section being taken on line 3 of Fig. 4 in the same plane as Fig. 2; Fig. 4, a plan section taken on line 4 of Fig. 3; Fig. 5, an enlarged plan section taken on line 5 of Fig. 1; Fig. 6, a section taken on line 6 of Fig. 7, giving a top plan view of a cross-head; Fig. 7, a section taken on the irregular line 77 in Fig. 6; Fig. 8, an elevation of a detail of the construction of the cross-head, showing it connected with an oil-supply pipe or piston; Figs. 9 and 10, enlarged broken sections taken, respectively, on lines 9 and 10 of Fig. 2; Fig. 11, a diagrammatic view of an extended form of toggle-operating mechanism which may be employed in place of that shown in Figs. 1 and 2, and Fig. 12 a rear elevation of the toggle mechanism shown in Fig. 11.

The shell or frame of the compressor A comprises a base-section A', an intermediate section A², a removable cover-section A³, a com-

pressor-cylinder A⁴, and a removable cylinder-head or cap A⁵.

E is a drive-shaft journaled toward opposite ends in boxes *t* at the opposite inner sides of the shell or casing and provided beyond the casing with fly-wheels E' E', one of which may be the driving-pulley. The shaft E is in the form of a crank-shaft, to which is secured one end of a pitman or connecting-rod F.

10 G is a toggle-lever having a lower arm or member G' and an upper arm or member G². The arm G' is mounted to rock upon or with a shaft s, journaled or mounted in bearings s' in the base of the chamber or section A'.

15 In the shell-section A² are cross-head guides r r. The arms or members of the toggle G are pivotally connected together by means of a pin or shaft G³, to which the connecting-rod F is pivotally secured. The construction of 20 the joint may be as most plainly shown in Fig. 2.

G⁴ is a cross-head provided at opposite sides with blocks or shoes q, which move in the vertical guides r. Extending transversely 25 through the cross-head is a pin or bolt p, with which the toggle-arm G² is pivotally connected at its upper end, as shown.

The compressor-cylinder A⁴ comprises a chamber I, surrounded by a water-jacket n, 30 having an inlet-pipe n' and an outlet-pipe n². At the lower side of the cylinder is a gas-induction port m, communicating with a vertical gas-induction passage m', cored in the shell. Extending to the passage m' is a horizontal passage m², cored in a boss m² on the side of the shell and having a threaded mouth m⁴, to which the return pipe or conduit of the expansion-coil leads. Extending through the cap or cylinder-head A⁵ is a central vertical 35 opening l, surrounded at the top by an annular seat l' and tapered at its lower end to present a seat or shoulder l². The opening is enlarged at l² to afford an annular chamber communicating with the gas-eduction 40 passage l³, cored in the head A⁵ and communicating with a vertical passage l⁴, cored in the part A⁴, terminating in a horizontal passage l⁵, having a threaded mouth l⁶, from which extends the gas-discharge pipe II. Fitting 45 the opening l is a cylindrical valve shell or chamber k, tapered at its lower end to fit the seat l² and afford an annular valve-seat k', surrounding the eduction-port of the cylinder. In the wall of the shell k at the chamber 50 k³ is an annular series of openings k². Fitting upon the upper end of the valve-shell k is a valve-stem guide k³, having a reduced downward-extending part k⁴. The upper end of the opening l is closed by means of a cap- 55 plate k⁶, having a central upward-extending boss k⁵, and held in place with bolts k⁷. Extending through the cap-plate k⁶ is a screw k⁸. Fitting the seat k' is the gas-eduction valve k⁹, having a stem k¹⁰, which passes 60 loosely through the guide k³ into an air-cushioning cup k¹¹, held in place by the screw k⁸. Surrounding the reduced portion k⁴ of the

guide and bearing against the valve to press the latter normally to its seat is a spring k¹².

The construction of all the parts in the opening l is such that the valve and the valve-seat may be quickly removed and replaced when desired and held when in place with great security. The valve k⁹ is cushioned against shock in rising by the entrance of its stem into the air-cushioning cup k¹¹. When the valve k⁹ is closed, its under face is in the plane of the under face of the cylinder-head A⁵.

In the chamber I of the cylinder is a piston I' upon a stem I², which at its lower end is 80 adjustably secured to the cross-head G⁴. At the lower end of the chamber I is a stuffing-box K, through which the piston-stem works.

It is a fact well known in this art that any lubricating-oil finding its way into the refrigerating-coil works injury, for the reason that it tends to coat the inner surface of the coil and detract, owing to its non-conducting properties, from the refrigerating efficiency of the coil. For this reason many and various more 85 or less ingenious traps have been interposed between the compressor and refrigerating-coil to catch particles of oil carried by the ammonia from the compressor. It is one of my ob-

jects in the present construction to prevent 90 any or at least any material quantity of oil from being brought into contact with the gas at the compressor, and while it is necessary that the piston-stem shall be lubricated to reduce friction at the stuffing-box the construction of the stuffing-box shown and to be described effectively precludes any material quantity of oil from entering the piston-chamber. The stuffing-box K comprises a casting 95 having the cylinder portion i and a flange i', at which it is secured in place between the shell-sections A² A⁴, as shown. At the top the cylinder has a reduced portion i' just large enough for the free passage of the piston-stem. In the cylinder or tube i is an oiler-bearing 100 K', comprising a ring having upper and lower flanges h, which fit the wall of the tube i and afford openings at the upper and lower ends of the bearing-piece just large enough for the ready passage through them of the piston-stem. Thus, as shown most plainly in Fig. 3, 105 inner and outer concentric chambers h' h² are formed, which communicate through an annular series of openings h³. In the side of the tube i is an oil-port i³, to which leads an oil-supply pipe i' from a suitable oil-reservoir i⁵. (See Fig. 1.) Above and below the oiler-bearing K' are packing-rings K², preferably of suitable fabric, the tube being closed at its lower end by means of a gland K⁸, adjustably 110 tightened in place by means of a screw-cap K⁴ to hold the oiling and packing rings properly in place. The packing-rings permit the stem to carry off just enough oil to properly lubricate it, the tendency of any surplus oil being 115 to work its way downward rather than upward. The lower end of the chamber I of the cylinder extends slightly below the inlet-port m, and any oil cut from the piston-stem by the

ammonia-gas will fall into the trap thus provided. As in practice but little oil will accumulate in this trap, it is not thought necessary to provide an outlet therefor. The trap may be cleaned at any time when the machine is being overhauled and the piston removed. If desired, a hard, pulverulent, or plastic lubricant may be employed instead of oil at the oiling-bearing; but the practical operation of the present machine has demonstrated that no material or, in fact, appreciable amount of oil enters the compressor-chamber from the piston-rod lubricator. The piston I' contains a chamber f, to which openings f' lead from the under side of the piston. At the top of the chamber f is a cap-plate f², fastened in place with screws, as indicated, and holding the piston-ring f³ in place. In the top of the cap-plate f² is an outlet-port surrounded by a flaring valve-seat f⁴, and below the said port is a spider f⁵, forming a guide for the stem f⁶ of an upwardly-lifting valve f⁷, which closes against the seat f⁴. Below the spider the stem f⁶ carries a nut f⁸, against which bears a confined spring f⁹, which tends to press the stem downward and hold the valve closed. The valve f⁷ when closed extends at its upper face flush with the end face of the piston, and, as before stated, the valve k⁹ at its under face extends flush with the face of the cylinder-head. Thus when the piston is moved to the cylinder-head clearance is absolutely avoided.

Extending vertically through the cylinder-head A⁵ is an opening m⁵, threaded at the top and tapered and reduced at its lower end m⁶ to afford a valve-seat. A reduced passage m⁷, cored or drilled in the cylinder-shell A⁴ and cylinder-head A⁵, extends from the induction-passage m' to the passage or opening m⁵. Working in the opening m⁵ is a valve m⁸ upon a stem m⁹, passing through a stuffing-box m¹⁰, screwed into the upper end of the opening. The stem m⁹ is provided with a handle m¹¹. Below the beveled seating-face of the valve m⁸ is a projection m¹², which fills the port at m⁶. The stem m⁹ is threaded and passes through a threaded opening in the stuffing-box m¹⁰, this being a common construction, whereby when the handle m¹¹ is turned to the left the valve m⁸ is raised from its seat to open communication between the induction-passage m' and cylinder above the piston. When the handle m¹¹ is turned to the right, the valve m⁸ is seated, its lower end extending flush with the lower face of the cylinder-head to avoid all clearance between said face and the piston.

The general operation of the apparatus is in the main the same as other apparatus of this character. Return gas entering the port m is compressed in the cylinder by the piston and discharged through the port k' and passages l⁴ l⁵ l⁶ to the pipe II. When the gas has done its work in the expansion-coil, it is returned through the port m⁴ and passages m² m' to the cylinder-chamber I. In the down-stroke of the piston I' the gas beneath it in

the chamber I opens the valve f⁷ and passes above the piston. In the rise of the piston the said gas is forced through the port k', 70 opening the valve k⁹ against the back pressure in the system, and thus compressing the gas.

To produce the best results and prevent waste of power, there should be absolutely 75 no clearance between the piston and cylinder-head. The expansive force of the gas when compressed as compared with that entering from the return-pipe may be as one hundred and twenty pounds to twenty pounds, more 80 or less, whereby a clearance one-eighth of an inch or even less would cause a piston having a traverse of five or six inches to perform no useful work. No valve which lifts from its seat and is seated by the back pressure of 85 fluid under the suction action of a piston will close without permitting the retrogression of more or less fluid through the valve. In other words, were the valve k⁹ not to close until the piston turns upon its downstroke a 90 certain quantity of compressed gas would be drawn or sucked back into the cylinder and by its expansion prevent the piston from doing useful work throughout more or less of its stroke. For the sake of economy, therefore, it is necessary that the piston shall remain practically quiescent at the end of its upstroke for a period sufficiently prolonged to permit the valve k⁹ to close before the piston starts upon the downstroke. The principal object of the toggle construction which I have shown and described is to accomplish this result and absolutely preclude the retrogression of gas through the valve k⁹ in the descent of the piston. In the construction 100 shown in Figs. 1 and 2 in the rotation of the drive-shaft the piston will ascend nearly three-quarters of the distance of its traverse in the first quarter-revolution of the shaft and rise at gradually-slowing speed to the 105 top of the cylinder. There while the levers are at the dead-center and the crank is crossing the dead-center the piston remains practically quiescent for a period long enough to permit the valve k⁹ to close. The piston-stem 110 at its lower end is screwed into a socket in the top of the cross-head G⁴, as shown in Fig. 3. The object of this construction is to render the stem adjustable to a limited extent to 115 adjust the piston toward or away from the cross-head, and in practice this adjustment should be such that the piston will just touch without apparent impact against the under face of the cylinder-head when it reaches the limit of its rise. Thus as the valves when 120 closed are flush with the surrounding surfaces practically no clearance will exist and all gas will be expelled. While the piston is practically at a standstill, the eduction-valve k⁹ closes and in closing expels the gas upward 125 from between it and its seat. Thus when the piston starts on its downstroke it leaves no gas above it to expand and interfere with its useful work.

130

If it is desired to prolong the practical stoppage of the piston at the end of its upward stroke, the connecting-rod F may be shortened slightly by screwing it a little farther 5 into the coupling F', which joins it to the toggle-lever, so that the toggle-lever will be drawn slightly past its dead-center. A further great advantage of this construction involving the toggle mechanism lies in that it 10 greatly reduces the power necessary to produce a given compression, for the reason that the leverage increases as the resistance increases.

Taking into consideration the resistance of 15 the spring k¹², which it is desired to employ, and the quickness with which it will close the valve l⁹, the compressor shown in Fig. 1 may be run at, say, two hundred revolutions per 20 minute and allow just sufficient time while the piston is at the end of its upstroke for the valve to become firmly seated before the piston starts to descend. When a materially-greater speed is desired, I prefer to provide a 25 construction according to the diagram shown in Fig. 11. In this construction the connection between the toggle-lever G and the connecting-rod F is through an intermediate toggle N, the arms of which are somewhat longer 30 than the distance from the joint of the toggle G to the points of connection of the arms of the toggle N with the arms of the toggle G. In the rotation of the drive-shaft the piston will move only about one-fifth of the distance of 35 its traverse in one-quarter revolution and the rest of the distance in the next quarter-revolution. Thus the time during which the piston remains apparently at rest at the top of its stroke may be greatly prolonged and give 40 as protracted a time for the valves to close when the drive-shaft is running at three hundred revolutions per minute, as is the case in the other construction running at two hundred revolutions per minute. A further 45 advantage gained by the construction illustrated in Figs. 11 and 12 is that a much shorter crank may be employed upon the drive-shaft to produce the same traverse of the piston, which by thus greatly increasing the leverage of the crank-shaft decreases to a very material extent the power necessary for driving 50 the machine.

It is very desirable to dispense with oil-cups at the joints of the mechanism, for the reason that they must be filled at intervals, and thus 55 require more or less constant attention. In the place of oil-cups I provide the following automatic lubricating means for the shaft, connecting-rod, and toggle-bearings.

The base portion A' of the compressor-casing 60 forms an oil-receptacle, which may be filled with a lubricating-oil to, say, the plane x. This causes the crank to dip into the oil with each revolution and lubricate the bearing thereon for the connecting-rod. Fastened in 65 one side of the base portion is a stem c, carrying on the inner side of the base a head or clamp c'.

P is a pump having a cylinder b in the form of a tube open at its upper end and closed at its lower end and provided near its lower end 70 with inlet-openings b'. Working in the cylinder b is a piston in the form of a hollow tube b², contracted at its lower end, as shown in Fig. 9, and having there an inlet-opening b³. In the lower end of the tube b² and normally closing the opening b³ is a movable ball-valve b⁴. The pin or bolt p, which forms the connection between the toggle-arm G² and the cross-head, is provided internally with a longitudinally-extending passage p', (see Fig. 5,) 80 opening at one end into a threaded socket p² in the under side of the pin. Extending from the passage p' are radial outlet-openings p³, leading to the surface of the pin at the cross-head and toggle-arm. The hollow piston b² 85 is screwed at its upper end into the socket p². The cylinder b of the pump may be raised and lowered in the supporting-head c' to increase or diminish the working stroke of the piston b². It will be understood that the farther the piston b² passes below the openings b' the more oil will be drawn into the cylinder with each operation and discharged. The piston b² rises and falls with the cross-head G². The oil discharged into the passage p' 90 passes for the most part through openings p⁴ into chambers p⁵ in the shoes q, and thence through openings q' to the surfaces of the guides r. At the lower ends of the guides r I provide troughs r' r², respectively, which 100 are open at the top and closed at opposite ends and receive the oil which trickles down the guides r. Extending from the center of the trough r', as shown in Fig. 1, is a pipe or duct r³. The rear end of the connecting-rod coupling or bearing-head F' is provided with a flaring opening a, leading to the pin G³, (see Fig. 10,) and the pipe r³ terminates above the path of the opening a, where the connecting-rod 105 nears the limit of its movement in the backward direction. Thus each time the connecting-rod moves in the backward direction the opening or receptacle a passes beneath the pipe r³ and receives part of the oil discharged from the latter. From the receptacle a the 110 oil passes into the bearing through a duct a' to lubricate the toggle-joint. Pipes or ducts r⁴ extend from opposite end portions of the trough r² to the bearings t of the shaft E, whereby oil trickling into the trough r² will 115 be conducted to the said bearings t to lubricate them.

In each side of the section A² are openings w for ready access to the interior of the shell. These openings I provide with tightly-fitting 120 but readily-removable doors w' for the exclusion of dust and to prevent oil from splashing out of the casing.

As before stated, one of the principal objects of my present invention is to reduce the 125 running expenses of a plant of the class to which this invention relates to the minimum. In order that there shall be no waste of power in the compressor, it is necessary to have no

clearance between the piston and cylinder-head, so that all the gas will be expelled in the upstroke of the piston. It is also necessary that the eduction-valve shall close before the piston starts on its downstroke to prevent any retrogression of compressed gas through the eduction-valve. The construction described accomplishes these objects by causing the piston to have a practically intermittent movement instead of a regular reciprocation, the interruption or stoppage of movement taking place when the piston is at the point nearest the eduction-valve. In practice the change in angle of the various lever mechanisms and natural looseness of joints will tend very materially to prolong the actual stoppage of the piston in the final extending and flexing movement of the toggle when both the driving-crank and toggle-lever are at or crossing their dead-centers. It may be stated that in watching the operation of the construction shown in Figs. 1 and 2 while the shaft turns at one hundred and twenty-five revolutions per minute the eye can detect an appreciable prolonged stoppage of the piston at the end of the upstroke, while none can be detected at the end of the downstroke. Whether driven directly from the crank or through the toggle mechanism, as described, the piston must reciprocate once with every revolution of the drive-shaft; but by the apportionment of time or change in the speed of the piston by making the latter move quickly where quickness is economy, and more slowly, even to stoppage, where economy requires it, I produce results which, so far as I am aware, cannot be effected in any other way. In the construction shown in Figs. 11 and 12 there is a still greater saving in power, as well as prolongation of the time between the ascent and descent of the piston.

When the compressor is initially started, there is a back pressure in the system against which the piston has to work when it commences the compressing operation. In a compressor which requires, say, a one-horse-power motor to keep it in operation after it has been started a motor of nearly two-horse capacity would be required to start the compressor were it to operate in its initial movements to compress the gas. To overcome this difficulty, I provide the valved starting-passage m^5 m^7 described. In operation before starting the compressor the valve m^8 is raised by turning the handle m^{11} to open communication between opposite sides of the piston. Therefore when the compressor is started the gas above the piston is forced through the port m^6 and around to the under side of the piston, and as the piston descends gas flows from beneath the piston around through the starting-passage to the upper end of the compressor-chamber. In this way the piston meets with practically no resistance, the valve being left open until the fly-wheels are at full speed. When the valve m^8 is closed after the fly-wheels have reached full speed, the compression of

the gas is performed with the least expense of power. This feature of my invention is very important in those places where, as before stated, the power is rented, because a one-horse-power compressor may be run with a one-horse-power motor and the rental would be of a one-horse-power motor instead of a motor having the capacity of two-horse power.

I have designed all parts of the mechanism shown with a view to economy both in construction and operation, and it requires no especially-skilled attendant either for running it or for the adjustment or replacement of parts at any time. All moving joints are oiled by the machine automatically, as described, and the shell is rendered practically dust-proof. Thus the apparatus requires practically no attention except for starting and stopping it.

While I prefer to construct my improvements throughout as shown and described, they may be modified in various ways, both in the matter of their arrangement and details of construction, without departing from the spirit of my invention as defined by the claims.

What I claim as new, and desire to secure by Letters Patent, is—

1. In a refrigerating-machine, the combination of the compressor-cylinder having in its discharge end an eduction-port communicating with the discharge-conduit, an inwardly-closing valve at said port, a piston in the cylinder, and toggle mechanism for driving the piston to avoid clearance at the end of its discharge-stroke and for interrupting the movement of the piston for a period sufficiently prolonged to allow the valve to become seated before the piston advances upon its suction-stroke.

2. In a refrigerating-machine, the combination with the compressor-cylinder and the gas return and discharge conduits, of an eduction-port in the cylinder-head communicating with the discharge-conduit, an inwardly-closing valve at said port, a piston in the cylinder, and means for operating the piston to move the same to the cylinder-head approximately without clearance, comprising a toggle-lever mounted to rock at one of its arms on a fulcrum and operatively connected at its other arm with the piston, and toggle-lever-driving means geared to the toggle-lever to flex the same to one side, to produce the suction-stroke of the piston, and to extend the same to a dead-center, to produce the discharge-stroke of the piston, and at the end of the discharge-stroke to interrupt movement of the piston for a period sufficiently prolonged to permit seating of the eduction-valve before the piston advances upon its suction-stroke, substantially as and for the purpose set forth.

3. In a refrigerating-machine, the combination with the compressor-cylinder and the gas return and discharge conduits, of an eduction-port in the cylinder-head communi-

- eating with the discharge-conduit, an inwardly-closing valve at said port, a piston in the cylinder, and means for operating the piston to move the same to the cylinder-head 5 approximately without clearance, comprising a toggle-lever mounted to rock at one of its arms on a fulcrum and operatively connected at its other arm with the piston, and toggle-lever-driving means comprising a crank-shaft 10 geared to the toggle-lever, to flex the same to one side and produce the suction-stroke of the piston, in the movement of the crank to one dead-center, and to extend the toggle-lever to a dead-center, and produce the discharge- 15 stroke of the piston, in the movement of the crank to its other dead-center, and interrupt movement of the piston at the end of its discharge-stroke for a prolonged period, whereby the seating of the eduction-valve is effected 20 25 30 35 40 45 50
4. In a refrigerating-machine, the combination with the compressor-cylinder and the gas return and discharge conduits, of an eduction-port in the cylinder-head communicating with the discharge-conduit, an inwardly-closing valve at said port, an induction-port toward the opposite end of the cylinder communicating with the return-conduit, a passage through the piston, an induction-valve on the piston for opening and closing said passage and extending when seated flush with the end of the piston, and means for operating the piston to move the same to the cylinder-head approximately without clearance, comprising a toggle-lever 60 mounted to rock at one of its arms on a fulcrum and operatively connected at its other arm with the piston, and toggle-lever-driving means geared to the toggle-lever to flex the same to one side, to produce the suction-stroke 65 of the piston, and to extend the same to a dead-center, to produce the discharge-stroke of the piston, and at the end of the discharge-stroke to interrupt movement of the piston for a period sufficiently prolonged to permit 70 seating of the eduction-valve before the piston advances upon its suction-stroke, substantially as and for the purpose set forth.
5. In a compressor, the combination with the compressor-cylinder, piston in the cylinder, and drive-shaft, of a toggle-lever mounted to rock at one of its arms on a fixed fulcrum, and operatively connected at its other arm with the piston, a pitman connected in eccentric operative relation to the shaft, and 80 intermediate toggle mechanism forming a connection between the said pitman and toggle-lever, substantially as and for the purpose set forth.
6. In a compressor, the combination with the shell having a base portion forming an oil-reservoir and supporting the cylinder, drive-shaft, piston, piston-stem and piston-stem-driving cross-head, of bearings for the drive-shaft on the inner sides of the said base provided with oiling-openings, a chamber in the cross-head having outlets to the cross-head guides, an oil-pump in the said base portion actuated from the compressor-driving mechanism and discharging into the said chamber, 95 and oil-conveying ducts extending from below said cross-head guide to the said oiling-openings at the drive-shaft, substantially as and for the purpose set forth.
7. In a compressor, the combination with the shell having a base portion forming an oil-reservoir and supporting the cylinder, drive-shaft, piston, piston-stem and piston-stem-driving cross-head, of bearings for the drive-shaft on the inner sides of the said base provided with oiling-openings, a chamber in the cross-head having outlets to the cross-head guides, an oil-pump in the said base portion actuated from the compressor-driving mechanism and discharging into the said chamber, 100 and oil-conveying ducts extending from below said cross-head guide to the said oiling-openings at the drive-shaft, substantially as and for the purpose set forth.
5. In a refrigerating-machine, the combination with the compressor-cylinder, and the gas return and discharge conduits, of an eduction-port in the cylinder-head communicating with the discharge-conduit, an inwardly-closing valve at said port extending when seated 55 flush with the inner face of the cylinder-head, an induction-port toward the opposite end of the cylinder communicating with the return-conduit, a passage through the piston, an induction-valve on the piston for opening and closing said passage and extending when seated flush with the end of the piston, and means for operating the piston to move the same to the cylinder-head approximately without clearance, comprising a toggle-lever 60 mounted to rock at one of its arms on a fulcrum and operatively connected at its other arm with the piston, and toggle-lever-driving means geared to the toggle-lever to flex the same to one side, to produce the suction-stroke 65 of the piston, and to extend the same to a dead-center, to produce the discharge-stroke of the piston, and at the end of the discharge-stroke to interrupt movement of the piston for a period sufficiently prolonged to permit 70 seating of the eduction-valve before the piston advances upon its suction-stroke, substantially as and for the purpose set forth.
